PIPE-CLEANING SEAL

Lawrence R. Robinson, Mount Lebanon, Kyle I. Robinson, Glenshaw, Earl O. Berger, Bellevue, and Walter S. Lang, Pittsburgh, Pa., assignors to Pittsburgh Pipe Cleaner Company, Pittsburgh, Pa., a corporation of Pennsylvania

Application June 4, 1946, Serial No. 674,302

2 Claims. (Cl. 286—16)

1

This invention relates to the cleaning of service water lines which extend from water mains to buildings.

Water mains in the street are tapped at the buildings in front of which they pass, and small service lines are connected to the mains for delivering water to the building. Close to the water mains, usually just behind the curb, there is a valve in each service line which is opened when water service is turned on for a building. The service lines gradually become obstructed by deposits of lime and the like, so it becomes desirable or necessary to clean out the lines. This can be done between the curb valve and the building by closing the curb valve, disconnecting the inner end of the line from the meter in the building, and driving a cleaning tool through the line from its open inner end to the valve. The common practice is to rotate the tool by means of a flexible cable while the tool is being driven forward by the cable. At intervals the valve is opened to flush out the debris that the tool has cut from the pipe. At such times feeding of the tool into the line is stopped, because the velocity pressure of the water against it would force the cable into a spiral inside of the pipe and cause so much friction that it either would prevent the cable from turning or would cause it to break. It will be understood that if the cleaning tool can not operate while the curb valve is open, then this system of cleaning cannot be employed for cleaning the service line between the curb valve and the main because that valve must remain open to accommodate the driving cable when the tool is beyond the valve. If this short section of pipe cannot be cleaned it may block off the rest of the line which can be cleaned, and thereby render cleaning of the latter futile.

It is among the objects of this invention to provide apparatus which permits a water service line to be cleaned throughout its length, and which permits the static pressure on the water main to be checked while the service line is being cleaned.

In accordance with this invention one end of a coupling or standard T having openings in its opposite ends is connected to the inner end of a service line after the line has been disconnected from a water meter in a building. A housing is connected to the opposite end of the coupling,

2

and a rotatable cable by which a cleaning tool is fed through the service line is passed through this housing and the coupling. Packing material is disposed in the housing to restrain leakage of water through it. The bottom of the coupling is provided with a water outlet which normally is closed by a flushing valve. With this valve closed and the curb valve in the service line open, the tool can be driven the full length of the service line because there is no velocity pressure resisting its advance. The coupling may be provided with a gauge which shows the static pressure on the main line. When it is desired to flush out the cuttings from the service line, the tool is stopped and the valve at the coupling opened. Connected to the packing housing is means for tightening up the packing whenever it becomes necessary in order to stop leakage through the housing. As there generally will be some leakage along the cable in spite of the packing, it is desirable to mount a reservoir on the outer end of the housing to collect such leakage. This reservoir is provided with a drain in its bottom. The cable passes through the reservoir. The reservoir may be directly connected to the packing adjusting means, and in such case the two are rotatably connected so that the reservoir will not be turned when the packing adjusting means is turned.

30 The preferred embodiment of the invention is illustrated in the accompanying drawings in which Fig. 1 is a side view of our apparatus; Figs. 2 and 3 are transverse sections thereof taken on the lines II—II and III—III, respectively, of Fig. 1; and Fig. 4 is a reduced side view of the apparatus in operative position at the inner end of a service line.

Referring to Fig. 4 of the drawings, a water main 1 in a street has a service line 2 extending from it through a foundation wall 3 of a building, such as a house or place of business. A few feet from the main and near the street curb there is a valve 4, called a curb valve, in the service line. This valve was opened when the water was first turned on for the building. There seldom is occasion for closing this valve thereafter, except when the service line is to be cleaned out. The curb valve then is closed to permit the inner end of the service line to be disconnected from the meter 6. In accordance with this invention re-

ducers 1 and 8 then are connected to the inner end of the line, and the larger reducer is screwed into an opening in one end of a coupling 9 which may be a standard T. In the opposite end of this coupling there is another opening in which one end of a tubular housing 10 is screwed. The two openings preferably are axially aligned. Between the two openings the bottom of the coupling is provided with an outlet to which a normally closed valve 11 is connected in conventional manner. Extending through the tubular housing and the coupling and into the service line is a flexible driving cable 12 to the outer end of which a suitable pipe cleaning tool 13 is connected. The cable is rotated and pushed ahead to feed the tool through the service line by means of apparatus 14 well known for this purpose.

Water from the service line is kept from escaping in any large amount through housing 10 by means of packing material with which the housing is filled. For this purpose a disc 16 provided with a central opening is welded in the inner end portion of the housing to form an end wall. One or more, preferably three, cylindrical packing members 17 of rubber or other suitable material are disposed face to face in the housing and are provided with axial openings 18 aligned with the opening in the end wall. The driving cable extends through and fills these openings. To press the packing against the cable and the inner surface of the tube, a compression bushing 19 is adjustably mounted in the outer end portion of housing 10. This bushing has a threaded portion that is screwed into the outer end of the housing and into engagement with the packing therein. The rest of the bushing is located outside of the housing and is provided with threaded radial openings in which rods 21 are screwed so that the bushing can be turned. When, due to wear of the cable against the packing members, water starts to leak through the housing in an appreciable quantity, the bushing is turned to screw it farther into the housing in order to compress the packing members further to stop most of the leakage. The leakage that does occur is caught in a reservoir 22 which is mounted on the outer end of the compression bushing. That is, two semi-circular plates 23 are bolted to the inner open end of the reservoir and project radially into an annular recess 24 in the bushing. This arrangement permits the bushing to be turned without turning the reservoir, the bottom of which is provided with a drain 26 that may empty onto the cellar floor or be connected by a hose 27 to a cellar drain. The outer end of the reservoir is provided with a small opening 28 through which the cable passes and in which it rotates.

To avoid any danger of the flexible cable buckling or looping in being pushed through reservoir 22 and coupling 9, a short tube is mounted in each chamber to compel the cable to remain straight. Thus, in reservoir 22 a tube 32 is welded to the outer face of bushing 19 around the axial passage through it. As this tube has a small internal diameter, the flexible cable 12 which extends through it can not buckle while the cable is being driven ahead. The tube is spaced from the outer end of the reservoir so that water can drip from the tube into the reservoir and be carried away through hose 27. A similar tube 33 is welded to disc 16 and extends far enough across coupling 9 to keep the cable from buckling therein, but not far enough to interfere with flushing of cuttings from the inner end of the service line 2.

In using this apparatus the curb valve 4 may be closed and the flushing valve 11 open or closed while the pipe is being cleaned between these two valves, or the curb valve may be opened only enough to allow a small flow of water through the service line in which case the other valve is left open. The cleaning tool then is driven into the service line to cut the deposits from its wall. After the tool has progressed a ways it is stopped and the curb valve opened wide to flush the debris from the pipe out through the coupling and open valve 11. If the curb valve has been left slightly open, a great deal of the cuttings will be flushed out continuously as fast as they are loosened from the pipe. When the cleaning tool reaches the curb valve the flushing valve is closed and then the curb valve is opened wide so that the tool can pass through it and proceed toward the water main. This can be done because, with the coupling valve closed, there is no velocity pressure against the tool which could prevent it from moving forward. At intervals the tool is stopped and valve 11 is opened to permit the service line to be flushed out. Whenever necessary, the packing in the tubular housing 10 is compressed by turning the compression bushing 19.

A pressure gauge 31 on coupling 9 permits the static pressure on the main line to be checked so that when meter readings are taken before and after cleaning the service line it can be determined whether or not any fluctuation in the static pressure in the main line may account for the difference in results obtained.

According to the provisions of the patent statutes, we have explained the principle and construction of our invention and have illustrated and described what we now consider to represent its best embodiment. However, we desire to have it understood that, within the scope of the appended claims, the invention may be practiced otherwise than as specifically illustrated and described.

We claim:

1. In apparatus for cleaning a water service line between a building and water main by means of a tool advanced through the line by a rotating cable, a housing having a cable-receiving passage through it, packing means in said housing for retarding leakage of water through it, manually rotatable means having its inner end threaded in one end of the housing for compressing said packing, said means having a cable-receiving passage therethrough, and a receiver for leakage from said housing provided with cable-receiving openings in its opposite ends and with a drain in its bottom, the outer end of said compressing means being rotatably mounted in one of said receiver openings to permit said means to be turned without rotating the receiver.
2. In apparatus for cleaning a water service line between a building and water main by means of a tool advanced through the line by a rotating cable, a housing having a cable-receiving passage through it, packing means in said housing for retarding leakage of water through it, a manually rotatable tubular member having its inner end threaded in one end of the housing and engaging said packing, the projecting outer end of said member being provided with a peripheral recess, means connected to said member between said recess and housing for turning said member to compress the packing, a receiver for leakage from said housing provided with cable-receiving openings in its opposite ends and with a drain in its bottom, the outer end of said tubular member pro-

jecting into one of said receiver openings, and retaining means secured to said receiver and projecting into said recess to support the receiver from said member and to permit the latter to be turned relative to the receiver.
